UNITED STATES PATENT OFFICE.

JACOB RICHTER, OF SOUTH CHICAGO, ILLINOIS.

AUTOMATIC FEED FOR BLAST-FURNACES.

SPECIFICATION forming part of Letters Patent No. 418,927, dated January 7, 1890.

Application filed March 8, 1889. Serial No. 302,555. (No model.)

To all whom it may concern:

Be it known that I, JACOB RICHTER, a citizen of the United States of America, residing at South Chicago, in the county of Cook and State of Illinois, have invented certain new and useful Improvements in Automatic Feed for Blast-Furnaces, of which the following is a specification, reference being had therein to the accompanying drawings.

10 This invention relates to devices for automatically feeding a blast-furnace; and it consists in the combination, with the elevator-platform for hoisting the ore, coal, and flux, of a car loaded with the material to be moved 15 upon the platform while below, and again over the mouth of the furnace while above, and vice versa, all by a single cable device, and again in a combination therewith of a device for automatically dumping the contents of the car into the furnace-mouth, all as 20 will be more fully hereinafter described and specifically claimed.

In the accompanying drawings, Figure 1 represents a vertical section of the top of the 25 furnace and of the adjoining elevator-tower, the same being provided with my improved devices for automatically feeding the furnace. Fig. 2 is a sectional view of the car and automatic dumping device; Fig. 3, an edge 30 view of the segment-gear and cam for the dumping device, and Fig. 4 a sectional elevation of the cable-winding spool and reversible driving-gear for the same.

Corresponding letters of reference in the 35 several figures of the drawings designate like parts.

A denotes the upper portion of a blast-furnace provided in its top with a feed-funnel *a*, closed by a conical bell-valve *b*, to be opened 40 by lowering by means of any well-known or usual device, so the material while dumping will have to slide over this valve *b* to be scattered and distributed. Upon the top of funnel *a* is fixed an inverted funnel *c*, both funnels *a* and *c* providing a large feed-hopper. 45

B is the elevator shaft or tower, built adjoining the furnace and connected with the top of furnace A by a bridge C, the top chords of which incline toward the furnace, so as to 50 overreach the funnel *c*, where again these top chords are horizontal. In this shaft B is arranged a platform-elevator D, of any usual

construction, hoisted or lowered by a wire rope *d*, passed over a pulley *e* and driven by steam or water power. This platform-elevator is provided with sheaves *f* and *g*, for purposes that will be hereinafter explained. 55

E is a hopper-car, being funnel-shaped in its bottom and supported on four flanged wheels *h*. This car has connected to each 60 end of its hopper the end of a wire cable *i* *j*, the opposite ends of which cables are secured upon a spool F, feathered upon shaft *k*, and having an elongated hub with two bevel friction-wheels G and H, engaging either one 65 with another bevel friction-wheel I, rigidly mounted upon a shaft *l*, which is driven from a steam-engine or other motor to be constantly rotating. Intermediate of wheels G and H the hub of spool F has formed an annular groove by flanges *m* for the forked end 70 of a shifting-lever, which by lateral shifting may bring either wheel G or H in contact with wheel I, to be rotated thereby in either one or the other direction, so as to wind one 75 cable *i* and unwind the other cable *j*, or vice versa, or by shifting the spool F half-way, so neither wheel C or H will touch wheel I, thereby releasing the spool F, to be rotated by the pulling of either cable *i* or *j*, or to remain stationary. The cable *i* is passed from 80 spool F over pulley J, pivotally secured to the bridge C and over pulleys *n*, *o*, and *L* off a stand M, secured upon the rear edge of the furnace to car E, and the cable *j* is passed 85 from car E over pulley *f* of elevator-platform D, thence around pulley N in the lower door of the elevator-tower B, thence over sheave O, exterior of and any required distance away from said tower B, and thence below the 90 track *p* and through an opening in the base of tower B to spool F.

The lowering of the car E is done by winding cable *j* upon spool F, whereby the car E will run down upon track-rails on top of bridge C, forming a continuation of a track on elevator-platform D, and after the car has arrived upon the elevator-platform the spool F is released from wheel I and the elevator-platform is lowered, whereby the cable 95 *i* will find a support upon a pulley R, pivoted in the sill of the top door of the tower B. During the time the elevator-platform is being lowered the cable *i* will unwind from 100

spool F, and proportionally the cable j will be wound thereon, and by the time the elevator-platform D will have reached the bottom of the elevator-shaft, where its track will 5 again form a continuation with track p, the cable j will have cleared the pulleys f and N, and then again applying power to spool F to pull the car horizontally to the location where it is to be loaded the cable i will pass around 10 pulley g, pivoted to the platform-elevator D. For moving and lifting the loaded car E to the furnace top the movements are the same, only in reversed succession.

The funnel-opening of car E is closed by a 15 conical valve S, suspended by a link r to a lever s, pivoted in a bracket t, which is secured upon one end of hopper E. The rearwardly-overhanging end of lever s is pivotally coupled with the upper end of a vertical bar u, guided in a bracket v, and this bar u 20 has pivoted at its lower end a roller w. A segmental gear-wheel T, pivoted to a bracket of the rear end of the car, has secured to it a cam-plate U, against the under face of 25 which the roller w bears, holding the valve S to its uppermost position for closing the funnel-mouth while the car E is being loaded and is being moved and elevated, until said car has reached the end of its trip over the top 30 of the furnace within about a foot, when the teeth of segment-gear T will engage the teeth of a horizontal stationary rack-bar V, so that with the rest of the motion of the car said segment-gear T will be turned, and with it 35 the cam U, thereby releasing the bar u to allow the lever s to swing and the valve S to drop, when the contents of car E will discharge into hopper c a of the furnace. The return movement of car E with releasing segment-gear T will turn again said gear and cam 40 U in a reverse direction, whereby the valve S is raised and closed again against the bottom mouth of the car E. With this arrangement

it will be seen the feeding of a furnace can be done entirely by machinery in an automatic manner. 45

What I claim is—

1. A device for feeding blast-furnaces, in which is comprised a tower, a platform-elevator, a bridge, extending from said tower and over the furnace to be charged, a surface-track, and a car provided with cables for pulling the same horizontally from and to the place where it is to be loaded, and after elevated pulling the same again horizontally to bring it over the mouth of the furnace and return again, all substantially as set forth. 50

2. A device for feeding blast-furnaces, in which is comprised a tower, a platform-elevator, a bridge extending from said tower and over the furnace to be charged, a surface-track, and a car provided with cables passed over pulleys at the farther end of the surface-track in the elevator-shaft and on top of the furnace to pull such car horizontally from 60 and to the place where it is to be loaded, and after elevated moving the same again horizontally over the mouth of the furnace and return again, and pulleys secured to the platform-elevator for guiding such cables while 65 the platform is on its lowest and uppermost positions, all substantially as set forth. 70

3. A device for feeding blast-furnaces, in which is comprised a car provided with a dumping-valve and a cam and a segment-gear connected with said valve, a stationary 75 rack arranged in juxtaposition to the furnace to be charged to actuate the segment-gear, and suitable means for conducting the car to and from the furnace. 80

In testimony whereof I affix my signature in presence of two witnesses.

JACOB RICHTER.
